CLAIM

The ornamental design for a frozen confection product as shown and described.

DESCRIPTION

FIG. 1 is a perspective view of a frozen confection product showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings illustrate portions of the frozen confection product that form no part of the claimed design.

1 Claim, 5 Drawing Sheets
